UNITED STATES PATENT OFFICE

MILFORD ATER, OF CHILLICOTHE, OHIO

KITE PARACHUTE

Application filed April 10, 1930. Serial No. 443,069.

My invention relates to a toy parachute, and while primarily intended for use in connection with an ordinary kite it will be obvious that the invention may be employed in connection with any other analogous devices or in any manner wherein it is found to be applicable.

Important objects of the invention are to provide a parachute of the character described, which will afford great fascination and entertainment to children, which embodies novel means for attaching same to a kite and for effecting its release while in flight with the latter in the air, and which may be readily attached to any type of kite already constructed as well as form a component part of a new kite structure.

Further objects of the invention are to provide a device of the class stated, which is simple in its construction and arrangement, strong, durable and efficient in its use, compact, positive in its action and comparatively inexpensive to manufacture.

With the foregoing and other objects in view which will appear as the description proceeds, the invention resides in the combination and arrangement of parts and in the details of construction hereinafter described and claimed, it being understood that changes in the precise embodiment of the invention hereinafter disclosed can be made within the scope of what is claimed without departing from the spirit of the invention.

In the drawings wherein like numerals of reference designate corresponding parts throughout the several views:—

Figure 1 is a plan view of a kite embodying my improved parachute, the latter being in the ascending collapsed position.

Figure 2 is a side view of the parachute in the descending expanding position.

Figure 3 is an enlarged, longitudinal, cross sectional view of the tubular connecting rod and of the associated balance weight.

Figure 4 is a plan view of the holding ring.

Figures 5 and 6 are side views of a modified form of connecting rod and weight, the former being in the ascending position and the latter in the descending position.

Referring in detail to the drawings 1 denotes a kite, which is provided with the usual control cord 2. The kite 1 may be of any conventional design and construction now in common use, and includes a short connecting tail 3.

A parachute 4 is connected to the kite 1 by a tubular connecting rod 5. The parachute 4 is of regulation conformation and comprises the air bag 6 provided with any suitable number of associated holding strings 7, which are joined with the perimeter of the latter in the usual manner.

The connecting rod 5 extends through and carries a spherical balance weight 8, which is preferably fixed in position centrally of the length of the former. The parachute 4 is permanently secured to one end of the connecting rod 5, and the kite 1 is detachably connected to the other end of the latter.

The converging ends of the parachute holding strings 7 are joined together and combinedly secured in one end of the tubular connecting rod 5, as indicated at 9, or in any other suitable manner.

The kite 1 is detachably connected to the other end of the tubular connecting rod 5 by a knot 10, which is tied in the free end of the short connecting tail 3, of the kite 1, and inserted into the tubular connecting rod 5, as clearly shown in Figure 3.

A holding ring or annulus 11 is mounted on and surrounds the parachute holding strings 7, and is provided for engaging the bunched perimeter of the air bag 6, while the latter is in the ascending collapsed position shown in Figure 1.

The parachute 4 virtually constitutes a balancing tail for the kite 1, and the air bag 6 thereof is constructed from any suitable,

light, flexible material to best meet conditions found in practice.

The operation of my improved kite parachute is as follows:—The kite 1 is first attached to the connecting rod 5 by inserting the tail knot 10 into the latter. Upon ascending, the parachute 4 will depend from the kite 1, and in consequence the holding ring 11 will drop by gravity to engage the bunched perimeter of the air bag 6 and maintain the latter in the collapsed position.

The engagement of the tail knot 10 in the connecting rod 5 is such that a pronounced jerk on the control cord 2, by the operator, while the kite 1 is in flight, will pull the tail knot 10 from the connecting rod 5 and thereby release the parachute 4 from the kite 1. As soon as the parachute 4 is so released from the kite 1, the weight and action of the balance weight 8, will turn the parachute 4 in the air, so that the air bag 6 will be disposed above the now depending connecting rod 5 and associated balance weight 8. When the parachute 4 is so turned in the air, the holding ring 11 will drop by gravity on the holding strings 7 to the balance weight 8, as shown in Figure 2, thereby releasing the air bag 6 and permitting the opening and inflation of the latter by the action of the air in a manner well known in the art. The parachute 4 will now descend slowly and may be retrieved by the operator for subsequent repetitions of the parachute flights in the manner stated.

The modified form of connecting rod 12 and balance weight 13, illustrated in Figures 5 and 6, differ from the preferred form hereinbefore described, in that the balance weight 13 is slidably mounted on the associated connecting rod 12 instead of being fixed thereto. The connecting rod 12 is provided with end flanges 14 to prevent the removal of the balance weight 13 therefrom.

A pair of strings 15 connects the balance weight 13 with the holding ring 16. The length of the strings 15 is such that the latter will be taut while the device is ascending, and the holding ring 16 is engaging the air bag 6 to hold the latter in the collapsed position.

When the parachute is released from the kite 1 the balance weight 13 will not only turn the parachute in the air, but will also slide by gravity on the connecting rod 12, thereby exerting a pull on the holding ring 16 to more effectively assure its release from the air bag 6 and permit the expansion of the latter to effect its proper descent.

While the embodiment of the invention is herein illustrated and disclosed as used in connection with a kite, it will be apparent that the parachute 4 may be elevated by use of a toy balloon or analogous device, or may be projected into the air by any suitable projecting apparatus. Of course, it is evident

that if the parachute is so elevated, the location of its descent could not be definitely determined, as its release cannot be regulated by any control element manipulated by the operator.

The present invention provides a novel and most entertaining device, which may be cheaply manufactured, and which does not require exceptional operating skill apart from the usual degree of dexterity involved in the successful manipulation of an ordinary kite.

What I claim is:

1. The combination with an elevating element, of a parachute including an air bag and a plurality of holding strings, a connecting member being secured to said holding strings and having a releasable attachment with said elevating element, a balance weight carried by said connecting member for turning and maintaining said parachute in its descending position in the air when released from said elevating element, and means mounted on said holding strings and engaging said air bag for securing the latter in the collapsed position while ascending, said means being shiftable on said holding strings for releasing said air bag to permit the opening and inflation of the latter while descending.

2. The combination with an elevating element, of a parachute including an air bag and a plurality of holding strings, a connecting member being secured to said holding strings and having a releasable attachment with said elevating element, a balance weight shiftably mounted on said connecting member for turning and maintaining said parachute in its descending position in the air when released from said elevating element, an annulus shiftably mounted on said holding strings and engaging said air bag for securing the latter in the collapsed position during the ascent of said parachute, flexible elements connecting said annulus with said balance weight, the movement of the latter in one direction on said connecting member disengaging said annulus from said air bag for releasing the latter and permitting its opening and inflation during the descent of said parachute.

3. The combination with an elevating element, of a parachute including an air bag and a plurality of holding strings, a connecting member being secured to said holding strings and having a releasable attachment with said elevating element, a balance weight shiftably mounted on said connecting member for turning and maintaining said parachute in the descending position in the air when released from said elevating element, an annulus shiftably mounted on said holding strings and engaging said air bag for securing the latter in the collapsed position during the ascent of said parachute, flexible elements

connecting said annulus with said balance weight, the movement of the latter in one direction on said connecting member disengaging said annulus from said air bag for releasing the latter and permitting its opening and inflation during the descent of said parachute, and means provided on respective ends of said connecting member for retaining said balance on the latter.

10 In testimony whereof I affix my signature.
MILFORD ATER.
